MACHINE FOR COVERING WIRE WITH A
HELICAL WRAPPING

Alexander John Sands, Westminster, London, England, assignor to The London Electric Wire Company and Smiths Limited, London, England, a corporation of Great Britain

Application October 5, 1936, Serial No. 104,124
In Great Britain August 18, 1936

4 Claims. (Cl. 117—41)

This invention relates to machines for covering wire or the like with a helical wrapping, more particularly for electrical insulation purposes.

The wrapping may be constituted by paper, cellulose cotton, wool or silk, preferably in ribbon or tape form and the machine employed is one in which a wire to be wrapped is continuously drawn through the centre of a rotary head arranged to rotate about the axis of the wire and carrying a disc-like roll, or similar convenient package of wrapping material which is wrapped helically around the wire by the combination of the axial movement of the wire and the rotary movement of the head which carries the wrapping material around the wire as it is unwound from the roll carried by the head.

When covering wire with a wrapping material for electrical insulation purposes, it is important that the tension in the wrapping material shall be as uniform as possible through the entire wrapping operation.

In the majority of machines of this nature, the package of wrapping material is carried on a rotatable sleeve, platform or similar suitable support which is capable of rotation independent of the head of the machine, and numerous proposals have been adopted for controlling the tension in the draw-off of the wrapping material, by the application of friction. In one form of construction the friction has been applied to the surface of a disc-like roll or similar convenient package of supply material which is carried on a rotatable sleeve, platform or other suitable support, such a construction however, being subject to centrifugal loads, also in certain cases damage to the wrapping material may result; in another form of construction, the friction is applied to the rotatable sleeve, platform or other suitable support which carries the disc-like roll or similar convenient package of wrapping material, but with such a construction, it is necessary for frequent adjustment to be made to compensate for the decrease in the diameter of the disc-like roll or similar convenient package of wrapping material. In yet another form of construction, the friction has been applied to the sleeve and has been controlled by the tension in the wrapping material. Such a construction however, is of necessity, very delicate and somewhat expensive to manufacture. The present invention aims at providing an improved, simple and efficient means whereby the tension in the supply material is maintained substantially constant throughout the wrapping operation.

In a machine for providing wire with a helical

wrapping, according to the present invention, means by which tension of the wrapping material is maintained substantially constant during an operation constituted by continuous substantial peripheral support of the package of wrapping material on the head.

Preferably, the machine comprises a plate adapted to rotate about a wire passing through its axis, the surface of which plate is so shaped or dished that an annular disc-like roll or similar convenient package of wrapping material, for example, paper, which is carried on said surface is in contact with said surface only at its peripheral edge at all periods during a wrapping operation.

The disc-like roll or similar convenient package is preferably located on a central boss rising from the plate and formed integral therewith.

A device embodying the invention is herein-after described and shown in the accompanying drawing:

Figure 1 is a sectional elevation taken on the line I—I of Figure 2 with the roller guide member 9 shown in full for the sake of clarity, and

Figure 2 is a plan view.

The head comprises a stationary sleeve bearing 1, on which the disc head 2 is mounted through a journal race 3. The disc head 2 has a central boss 4 which carries the journal races 3 and the driving pulley 3a and a central boss 4a adapted to locate the package hereinafter more particularly referred to.

This spigot 4a, also carries a covering plate 6 of known type, arranged with usual means 14 for pressing the wrapping tightly into position on the wire. An adjustable guide member 7 for the wrapping material is carried on the central boss 4a.

Around the central boss 4a, the head extends in disc formation 8 having a roller guide member 9 and a fixed inclined guide member 10 at points on its circumference. A dished plate 11 is secured to the disc 8 by means of bolts 12. A roll of paper strip 13 rests on the dished plate 11 at its periphery only and is maintained in its correct position by means of the package locating ring 5.

The operation of the head is as follows:

The wire 15 passes from a suitable source of supply through the stationary sleeve bearing 1 and through the covering plate 6. The paper strip 13 from the roll 13, passes around the roller guide member 9, around the fixed inclined guide member 10 and under the horizontal arm of the adjustable guide member 7, which guide member 7 ensures the correct lay of the paper strip for its 55

application to the wire 15. Finally, the paper passes around the wire 15, passing through the head in the direction of the arrow A. After the strip has been applied to the wire, it passes 5 through the device 14.

It is preferred to use that material known as bakelized fabric for the dished plate 11.

By mounting the disc-like roll or similar convenient package of the supply material on the 10 dished plate 11, it will be seen that the speed of rotation of the package 13 will be greater or less than the speed of rotation of the head, dependent upon the direction of such rotation in relation to the direction of the unwinding of the package, 15 and that the tension of the draw-off of the material will be dependent, to a large extent, on the friction between the peripheral edge of the said disc-like roll or similar convenient package and the surface of the dished plate 11.

20 It will be apparent that the external diameter of the package of wrapping material will steadily decrease as the material is applied to the wire and that the turning moment for a given tension in the material will also decrease in direct proportion to the diameter, and such decrease will be compensated for, by the reduction in friction between the peripheral edge of the package and the surface of the dished plate, which friction will decrease approximately in proportion to the 25 weight, i. e., in proportion to the reduction in face area of the package, whilst the braking effect of the friction between the centre of the package and the locating boss will tend to increase in direct proportion to the speed of rotation of the package in relation to the dished plate, with the result, that the tension in the draw-off of material will remain substantially 30 constant.

The co-efficient of friction between the surface 40 of the dished plate and the peripheral edge of the disc-like roll or similar convenient package may be modified by the selection of various materials for the surface of the dished plate and/or by preparation of such surface in various ways.

45 The degree of tension in the material may be further controlled by the relative dimensions of the package, the preferred annular disc form consisting of a single width of the material wound in a continuous spiral or convolute formation being modified by traversing the material during winding to produce a package of disc-form, but having a thickness greater than the single width of the material. It will be readily apparent, that such a modified package will result 50 in an increase of the tension in the material during the wrapping operation according to the increase in the width of the package.

What is claimed is:—

60 1. In a machine for providing wire with a helical wrapping, a disc-like head, said disc-like head

being arranged to rotate about a wire which passes vertically through the axis of said head, an annular package of wrapping material in tape-like convolute form supported on said disc-like head having an effective contact with said head at the periphery of said package only, so that the tension in the wrapping material is maintained constant by the weight of the wrapping material on the surface at all periods during a wrapping operation. 5

2. In a machine for providing wire with a helical wrapping, a disc-like head, said disc-like head being arranged to rotate about a wire which passes vertically through the axis of said head, a central boss, said boss rising from the centre 10 of said head and rotating therewith, an annular package of wrapping material in tape-like convolute form supported on said disc-like head and held in position thereon by said central boss, a dished surface to said disc-like head, said annular package being supported only at its periphery on said dished surface so that the tension in the wrapping material is maintained constant by the weight only of the wrapping material on the dished surface at all periods during a wrapping 15 operation. 20

3. In a machine for providing wire with a helical wrapping, a relatively flat disc-like head, said disc-like head being arranged to rotate about a wire which passes vertically through the axis of said head, said head having a dished upper surface, an annular package of wrapping material in tape-like convolute form supported on said dished surface of said disc-like head, said annular package being supported only at its periphery on said dished surface so that the tension in the wrapping material is maintained constant by the weight only of the wrapping material on the dished surface at all periods during a wrapping 30 operation. 35

4. In a machine for providing wire with a helical wrapping, a disc-like head, said disc-like head being arranged to rotate about a wire which passes vertically through the axis of said head, a central boss, said boss rising from the centre 40 of said head and formed integral therewith, a flat surface to said disc-like head, a dished surface located on said flat surface of said disc-like head, an annular package of wrapping material in tape-like convolute form supported on said dished surface and held in position thereon by said central boss, said annular package being supported only at its periphery on said dished surface, so that the tension in the wrapping material is maintained constant by the weight of the wrapping material on the dished 45 surface at all periods during a wrapping operation. 50
